CLAIM

The ornamental design for a holder for small personal items, as shown and described.

DESCRIPTION

FIG. 1 is a top perspective view of a holder for small personal items showing our new design;

FIG. 2 is a bottom perspective view thereof;

FIG. 3 is a front view thereof;

FIG. 4 is a back view thereof;

FIG. 5 is a left elevation view thereof;

FIG. 6 is a right elevation view thereof;

FIG. 7 is a top view thereof; and,

FIG. 8 is a bottom view thereof.

The broken lines shown in the drawings depict portions of the holder for small personal items that form no part of the claimed design.

1 Claim, 7 Drawing Sheets
